UNITED STATES PATENT OFFICE.

WILLIAM M. MITCHELL, OF LOUISVILLE, KENTUCKY.

RAIL-ANCHOR.

1,235,495.

Specification of Letters Patent.

Patented July 31, 1917.

Application filed April 9, 1917. Serial No. 160,630.

To all whom it may concern:

Be it known that I, WILLIAM M. MITCHELL, a citizen of the United States, and a resident of Louisville, county of Jefferson, and State 5 of Kentucky, have invented certain new and useful Improvements in Rail-Anchors, of which I do declare the following to be a full, clear, and exact description, reference being had to the accompanying drawings, forming 10 part of this specification.

The present invention has for its object to provide a simple, cheap and effective construction of rail anchor adapted to prevent the "creeping" of railway rails; and 15 to this end the invention consists in the features of novelty hereinafter described, illustrated in the accompanying drawings and particularly pointed out in the claims at the end of this specification.

20 Figure 1 is a view in side elevation and Fig. 2 is a plan view showing part of a railway rail, cross ties of a track and a rail anchor embodying my invention. Fig. 3 is a view in central vertical cross section 25 through Fig. 2, parts being shown in elevation. Fig. 4 is an enlarged detail view showing the joint between the anchor member and the stud or projection on the rail flange. Fig. 5 is a view similar to Fig. 2 but showing a modified form of the invention. Fig. 6 is a view in central vertical cross section through Fig. 5.

Referring more particularly to the form of the invention illustrated in Figs. 1 to 4 35 of the drawings, A designates the cross ties of a railway track and A' denotes one of the rails mounted thereon and suitably spiked thereto. To one side of the center of the rail A and preferably to one of its base 40 flanges a, is connected a stud or projection B adapted to be engaged by a suitable anchor member C that will be conveniently connected to one, or preferably a plurality, of the cross ties A of the track. The stud or 45 projection B may consist of a short post or section of a bar that is united to the rail (preferably to the base flange a), by fusing or welding the stud to the base flange as by means of a portable oxy-acetylene torch. 50 That is to say, that portion of the rail base flange to which the stud or projection B is to be attached is first heated to approximately the fusion point by the torch and the stud is then fused to the flange by aid of the torch, a fillet of metal fused from a steel 55 rod or pencil being preferably run between

or around the base of the stud or projection B and the base flange a of the rail. By this means the stud is solidly and permanently united to the rail, becoming, in effect, an 60 integral part thereof.

The anchor member C may be made in a variety of forms, one simple form being the bar C having end portions c adapted to extend over a plurality of cross ties, these end 65 portions c being formed with holes to receive spikes c' by which the anchor member C is connected to the cross ties. A portion of the anchor member C is bent inwardly and slightly upwardly as shown at C' and is 70 formed with an opening c² adapted to set over the stud or projection B to firmly engage or interlock with said stud or projection. Preferably the stud or projection B is provided at its free end with a suitable 75 offset b adapted to prevent any accidental disengagement of the anchor member C from the stud. As shown in Figs. 1 to 4, the stud B may be formed with an offset or head of oval shape, the major axis of this offset extending obliquely to the line of the rail A' and the hole c² in the inwardly bent portion C' of the anchor member C may be formed of an oval shape corresponding to the shape of the head b of the stud B but the major 80 axis of this hole c² will extend parallel with the line of the rail A'. In applying the anchor member A to the stud B, the anchor member will be turned obliquely to the line 85 of the rail A' so that the head or offset b of the stud B may enter the oval-shaped hole in the portion C' of the anchor member, after which the body of the anchor member C will be turned slightly to a position 90 parallel with the rail A' and the portion c of the anchor member C will then be spiked to the ties. When the anchor member is thus in position for use, it will securely hold 95 the rail against creeping in either direction and all danger of the loosening of the anchor 100 member or its disengagement from the rail will be effectively overcome.

It is obvious that the manner of applying my invention may be widely modified without departing from the spirit of the invention. Thus, in Figs. 5 and 6 of the drawings, I have shown a projection B² that is fused or welded to the outer edge of one of the base flanges a of the rail A' and with this stud or projection engages an anchor 110 member C² that has its end portions provided with spike holes to enable it to be at-

2
tached to the cross ties A of the track. The central portion of the anchor member C² is bent as shown at C³ and is formed with a hole to receive the stud or projection B². 5 The stud B² is preferably formed with an opening B³ to receive a cotter pin, a nail, or the like to more securely hold the anchor member in position upon the stud, although inasmuch as the anchor member is spiked to 10 the ties, the danger of any disengagement of the anchor member from the stud or projection B² is practically negligible. With this form of my invention, as with that hereinbefore described, it will be seen that when 15 the anchor member has been engaged with the stud B² and has been spiked to the ties, all danger of the creeping of the rail in either direction is avoided.

It is obvious that changes may be made in 20 the details set forth without departure from the essentials of the invention as defined in the claims.

Having thus described my invention, what I claim as new and desire to secure by 25 Letters Patent is:—

1. The combination with a railway rail and its supporting cross-tie, of a stud or projection welded to the rail, and an anchor member separable from the rail and adapted 30 to coöperate with said stud or projection and with said cross-tie to prevent the creeping of the rail.

2. An anti-creeper for railway rails comprising a stud or projection welded to the 35 rail and an anchor member engaging said stud or projection and having a part to engage a cross-tie or ties of the track.

3. An anti-creeper for railway rails comprising a stud or projection welded to the 40 rail and an anchor member having a part to engage a cross-tie or ties of the track,

and means for connecting said anchor member to said stud or projection.

4. An anti-creeper for railway rails comprising a stud or projection welded to the 45 rail, and a bar adapted to be spiked to a cross-tie and having a portion engaging with said stud or projection.

5. An anti-creeper for railway rails comprising a stud or projection welded to the 50 rail, and an anchor member having a hole to receive said stud or projection and having a portion adapted to be spiked to one or more cross-ties.

6. An anti-creeper for railway rails comprising a stud or projection welded to the 55 rail, and an anchor member having a bent and perforated portion to engage said stud or projection and having an end member for engagement with the cross-tie. 60

7. An anti-creeper for railway rails comprising a stud or projection welded to the base flange of the rail and an anchor member having a bent and perforated portion to fit over said stud or projection and having 65 an end member for engagement with the cross-tie.

8. An anti-creeper for railway rails comprising a stud or projection welded to the rail, and an anchor member having a centrally bent and perforated portion to engage 70 said stud or projection and having perforated end portions for engagement with the cross-ties of the track.

9. The combination with a railway rail 75 and its supporting cross tie, of an anchor adapted to coöperate with the cross tie to prevent creeping of the rail, and a stud fused or welded to the rail and arranged to hold said anchor removably in position 80 on the rail.

WILLIAM M. MITCHELL.
